UNITED STATES PATENT OFFICE.

IRVING L. STERN, OF NEW ORLEANS, LOUISIANA, ASSIGNOR TO HAVANA-AMERICAN CO., OF NEW YORK, N. Y., A CORPORATION OF NEW JERSEY.

CIGAR-PACKAGE.

1,151,415.

Specification of Letters Patent. Patented Aug. 24, 1915.

Application filed April 28, 1915. Serial No. 24,389.

To all whom it may concern:

Be it known that I, IRVING L. STERN, a citizen of the United States, residing at New Orleans, in the parish of Orleans and State 5 of Louisiana, have invented new and useful Improvements in Cigar-Packages, of which the following is a specification.

This invention relates to cigar wrappers and packages.

10 One of the objects of the invention is to produce a cigar package in which the cigar or cigars can be held in such a way as will tend to preserve the aroma and taste of the tobacco.

15 As is well known to tobacconists, cigars are extremely sensitive to their environment or immediate surroundings and unless care is taken in the manner in which they are packed for the trade they will deteriorate 20 and lose their peculiar character and flavor or take on an undesirable taste or flavor.

25 Cedar wood possesses very desirable qualities for preserving tobacco; its pungent odor blends with the odor of the tobacco and the odor of the cedar seems to have the effect, as it were, of insulating the cigars or tobacco from any bad effects which may be incidental to their environment. For these 30 and other reasons cedar wood is generally accepted as being the best material of its kind for use as a container for cigars because of the fact that it will not affect the character, aroma or quality of the cigars.

35 It is a common practice to construct cigar boxes of cedar wood, and although this method is efficient where the boxes are left closed, the beneficial effects arising are often completely lost from the fact that cigar boxes are often left open on the 40 counter. Furthermore, cedar wood is becoming very scarce and hence more expensive.

45 One of the objects of the present invention is to provide a package in which a film of cedar wood is intimately associated with the cigar and which will give the beneficial effects of the cedar, whether the cigar box be left closed or open; and, furthermore, to provide an arrangement which will enable 50 these beneficial effects to be brought about very economically, if desired.

55 The invention consists in the general combination of parts and details herein described, all of which contribute to produce an efficient cigar package.

A preferred embodiment of my invention will be particularly described in the following specification, while the broad scope of my invention will be pointed out in the appended claims.

60 In the drawing,—Figure 1 is a perspective, showing an open cigar package embodying my invention. Fig. 2 is a vertical section taken through the cigar package. Fig. 3 is a perspective of one of the cigars 65 removed from the box.

Referring more particularly to the parts, 1 represents a container which may be in the form of an ordinary cedar wood box such as is commonly used for packing cigars, and 70 this box may be provided if desired with a hinged cover 2 which in Fig. 1 is represented in open position.

75 Within the container or box 1, I provide a plurality of cigars 3 which may be laid in the box in regular rows in the usual manner.

According to my invention I arrange the 80 interior of the box so that each cigar is substantially surrounded with a film of cedar wood, and I prefer to accomplish this by producing a plurality of cells having a wall of cedar wood film, and in these cells I place the cigars. In the embodiment of my invention illustrated, I accomplish this result by

85 wrapping each cigar with a removable enveloping wrapper 4 of cedar wood film. These wrappers are simply applied to each cigar as a loose roll, and each roll may be held in place on its corresponding cigar by any suitable means, preferably by means of 90 a cigar band 5. These wrappers 4 are sufficiently long to protect the full length of the cigar and preferably are slightly longer than the cigars. When the cigars are packed in a

95 box in this way, each roll or wrapper 4 forms a cell enveloping each cigar on all sides with the cedar wood film. If a box packed with cigars in this way is left open, the scent of the cedar wood remains strongly in the atmosphere around the cigars and this effect occurs whether the rows of cigars are broken or not by the removal of any of the cigars.

100 If desired, the container or box 1 may be constructed of any wood other than cedar to reduce the cost of the container, and if 105 this is done, my package will still have a strong odor of cedar wood associated with the cigars and remaining with them until the contents of the box is consumed.

11 The wrappers act as protectors for the

cigars and if desired one or more of the cigars may be carried in one's vest pocket with the wrappers left on the cigars. In this way the beneficial effect of the cedar wood continues after the cigar is removed from the box.

When it is desired to smoke one of the cigars, it is removed from the box, and the band 5 is broken whereupon the wrapper 4 of the cedar wood film is removed.

I do not limit myself in the practice of my invention to the use of all the features of my invention in combination.

It is understood that the embodiment of the invention described is only one of the many forms or embodiments my invention may take, and I do not wish to be limited in the practice of my invention nor in my claims to the particular embodiment set forth.

What I claim and desire to secure by Letters Patent is:

1. As a new article of manufacture, a cigar having a removable enveloping wrap-
per of cedar wood film.

2. As an article for manufacture, a cigar

having a removable enveloping wrapper of cedar wood film, said film in the form of a loose roll and means for holding said wrapper on the cigar.

3. As a new article of manufacture, a cigar having an enveloping wrapper, consisting of a flexible sheet of cedar wrapped thereabout with its edges overlapping, and an encircling band for retaining the said wrapper in position upon the cigar.

4. A cigar package comprising an outer container having a cellular interior composed of walls of cedar wood film, and cigars packed in the cells formed by said cellular interior.

5. A cigar package consisting of a box having a plurality of cigars carried therein, said cigars each having an individual envelop composed of cedar wood film.

In testimony whereof I have hereunto set my hand in presence of two subscribing witnesses.

IRVING L. STERN.
